UNITED STATES PATENT OFFICE.

AUGUST J. MEYER, C. F. CLEVELAND, OHIO.

VARIABLE-SPEED-TRANSMITTING MECHANISM.

No. 882,952.

Specification of Letters Patent. Patented March 24, 1908.

Application filed January 26, 1907. Serial No. 354,169.

To all whom it may concern:

Be it known that I, AUGUST J. MEYER, a citizen of the United States of America, and a resident of Cleveland, in the county of Cuyahoga and State of Ohio, have invented certain new and useful Improvements in Variable-Speed-Transmitting Mechanism, of which the following is a specification.

My invention relates to improvements in variable-speed transmitting-mechanism, and has for its object the provision of apparatus of this character, which shall be simple, effective and shall be readily operated at widely varying ranges of speed, and in either direction. The most urgent demand for apparatus of this type, at the present time, is for a structure which shall best lend itself to the transmission of power upon motor vehicles, and my improvements have been directed particularly toward the solving of this problem, although it will be appreciated that my invention is in no wise limited to any specific application of the structure herein set forth.

Transmitting-mechanism, dependent upon gearing and the like for the purpose of varying speed, is restricted to relatively few ratios of speed-transmission, while presenting difficulties in starting or changing the speed during the actuation thereof.

My invention proceeds upon the lines of a suitable fluid-actuated mechanism, which serves to overcome these undesirable features, and presents advantages which will be better understood after my improvements have been set forth.

I may briefly and generally describe the embodiment of my invention in a preliminary way by stating that the driving member preferably is equipped with a plurality of vanes or blades rotating within a fluid-chamber, wherein is disposed a deflector acting in conjunction with said blades to confine the fluid under the impact of the blades to a greater or less degree, and thereby insure variation in the speed-transmission, or even operatively to disconnect the driving and driven members of the mechanism. The details thereof will be explained in connection with the accompanying drawings, wherein—

Figure 1 is a longitudinal sectional view through the power transmitting mechanism embodying my invention. Fig. 2 is an irregular cross section thereof taken on line

2—2, Fig. 1. Fig. 3 is an isometric view of the preferred type of co-acting blades or vanes employed in my improved structure. Fig. 4 is a similar view showing the same mounted in the cylindrical core and associated with one of the conical heads. Fig. 5 is a similar view of the deflector removed from the casing. Fig. 6 is a detail illustrating the controlling lever and releasing mechanism adapted for association with my transmitting appliance when employed on automobiles and the like, and Fig. 7 is a sectional view on line 7—7; Fig. 2, partially broken away at one end, which well illustrates the relation of the several operative parts.

Through each of the several figures of the drawing, I have employed the same character of reference to indicate similar parts.

Referring first to Fig. 1, it is seen that all of the operative mechanism is contained within the sealed-casing *a*, which is generally of cylindrical form, and is provided with circumferential heat-radiating flanges *a'*. It will be assumed that power is applied by any suitable motor device to the shaft *b* upon the left, and is to be imparted to mechanism connected with shaft *c* upon the right. Keyed upon shaft *b*, is a conical head or disk *d* closely fitting co-acting surfaces formed interiorly of the fluid chamber *f*. Valves *d'* control openings connecting interiorly with the central portion of said chamber and insure the maximum working pressure rearwardly of the disk *d*. A smaller conical head *e* is adapted to fit co-acting surfaces at the opposite end of said chamber, and is provided with an inwardly opening valve *e'*. Between these parts is secured the quartered core-member *g*, which mounts the double blades *h i*, (separately shown in Fig. 3) in position to act upon the fluid within chamber *f*, as the same shall be governed through the medium of the deflector *j*. The blades *h* are centrally cut away at *h'* to receive the connecting web *i'* of the co-acting blades *i*, and when these parts are mounted at right angles within the quartered core, they are adapted freely to move diametrically with respect to each other and the core, and in the corresponding slots provided in the conical heads or disks *d e*, in order that the deflector *j* may cause the blades or vanes to assume retracted or extended positions with respect to the quartered core, whereby their action upon the fluid within the chamber *f* is regu-

100

105

110

lated. The deflector *j* is provided with an upwardly-extending projection or projections *j'* interiorly fitting within the auxiliary chamber *f'*, and is provided with an inclined 5 face *j''*, which co-operates with the wedge *m* in governing the position of the deflector. Slots *a''* interiorly of the casing, receive the lower edges of the arched deflector, and connect rearwardly of the conical head or disk *d*. 10 Compression springs *j³* seated within the vertical openings *j''* normally tend to raise the deflector, and said openings *j''*, acting in conjunction with slots *a''* of the casing, serve materially to equalize the pressure rearwardly of disk *d* immediately 15 the upper or cutting-edges *j⁴* of the openings *j''* are raised above the interior edges *a³* of the slots *a''*. Openings *j⁵* afford free passage for the fluid-medium exteriorly and interiorly of the deflector, and the double valve *j⁶* likewise affords free passage for said fluid-medium from the auxiliary chamber, *f'*; all these parts insuring the immediate actuation of the deflector, as shall presently be described. 20 Splined upon the shaft *c*, which it will be understood is securely keyed to casing *a*, is provided a longitudinally movable collar *k* acted upon by controlling lever *l*. Said collar has an upwardly extending arm connected with the actuating wedge *m* by means of the rod *m'* extending through gland *m''*, said wedge acting upon the correspondingly inclined face *j''*. Thus by moving the wedge to the right, it is seen that the deflector will 25 be caused to rise through the action of the spring *j³*, and any working pressure within the chamber *f'*. The position of the deflector, accordingly, is placed entirely under the control of lever *l*, and consequently the ratio 30 of speed-transmission may be accurately governed thereby.

Referring to Fig. 2, and understanding that the chamber *f* is filled with any suitable fluid, such as glycerin, oil or the like, it will 35 be seen that inasmuch as said fluid is confined between the extended portions of blades *h* and *i*, and by the deflector, the shafts *b* *c* must rotate at a common speed, by reason of their connection through the practically non-compressible fluid-medium. The 40 tendency, of course, would be for the core and the blades to rotate within the fluid chamber, but said blades are restricted in their action by the deflector, and cause a 45 relatively high working pressure upon the fluid, which re-acts both to cramp the conical heads within their co-acting seats in the fluid chamber, and cause the casing and shaft *c*, keyed thereto, to rotate with shaft *b* and its 50 connected parts. The valves *d'*, opening outwardly, it will be understood, permit the maximum working pressure to act rearwardly of disk *d*, while the valve *e'* permits the escape of any fluid imprisoned forwardly 55 of disk *e*, thus enabling these parts to be 60

forced home to their seats. Assuming now that it is desired to reduce the speed, the lever *l* will be moved, actuating through the slip ring *k'*, collar *k* and rod *m'*, said wedge *m* to move toward the right and permit the deflector to be lifted in a corresponding degree. 70 This will afford a more or less constricted opening for the passage of the fluid-medium between the surface of the core *g*, or between the blades and the interior surface of fluid chamber *f*, thereby permitting lost motion between these parts, and driving the shaft *c* at a proportionately lower rate of speed. This effect will be increased upon the further withdrawal of the wedge part *m* until the 75 blades revolve without effect, centrally of the fluid chamber; being retracted as far as possible within the quartered core, and thereby operatively disconnecting shafts *b* and *c*. Immediately the openings *j''* are raised above 80 the receiving slots *a''*; the working pressure will be freely transmitted rearwardly of the disk *d*, inasmuch as said slots connect with that portion of the chamber beyond said disk, while the valves *d'* admit only of the 85 passage of the fluid toward this space, as well. Consequently, the working pressure must at all times be applied rearwardly of the conical disk or head *d*. During the operation, of course, it will be apparent that considerable 90 heat is developed in the fluid thus placed under pressure, but the same will find ample radiation through radiating flanges *a'*.

It should be observed that in my improved mechanism, the deflector is positioned within the fluid chamber to govern the action of the fluid-medium upon the blades or vanes, thereby dispensing with every form of valve for such purpose. Moreover, with the herein-described construction, 105 wherein the blades are permitted to revolve in a relatively large fluid-chamber, and restricted only to the extent required by the deflector-part, there is decreased wear, and less loss of power than in a construction 110 wherein merely the eccentricity of the entire fluid-chamber is altered, as for example, in the rotary pump shown and described in the patent to Duncan, No. 466,660, January 5th, 1892. 115

As applied particularly to motor vehicles, it will be seen that marked advantage results if the speed-transmitting-mechanism can be instantly thrown out of action at a moment's notice, and accordingly, in Fig. 6, I have 120 shown means whereby the lever *l* is thus placed under control of the motorist without removing his hands from the steering wheel. In this case said lever is connected by means of the rod *n* with a hand lever *o* acting upon the quadrant or rack *o'*. This rack is normally maintained in engagement with the detent *o''* through the action of the spring *o³*. The eccentric part *p* is connected with the 125 foot lever *q* by means of link *r*, and it will be 130

appreciated, that the quadrant or rack may at once be disengaged from the detent o'' by actuating the quadrant downwardly against the tension of its spring, whereupon the 5 spring n' , acting on rod n and lever l , will instantly force the associated wedge m toward the right, thereby releasing the deflector and disconnecting the transmitting mechanism, as already described.

10 It will be appreciated that because of the fact that my apparatus is longitudinally symmetrical, and is not dependent for establishing its working pressure upon any valve-mechanism, that the same may be employed 15 for transmitting motion at varying speeds in either direction of rotation, which is an advantage of marked importance in this class of apparatus. Moreover, the adjustment of its speed-transmission is gradual and 20 easy, thereby throwing no undue strain upon the motor or associated mechanism. The range of speed too, is embraced within wide limits, since the position of the deflector controls the same, and this may be very closely 25 regulated.

Having now described a mechanism embodying my invention, I claim as new, together with such modifications as may be made by those merely skilled in the art, the 30 following:—

1. In apparatus of the class described, the combination with driven and driving members, of an associated fluid-chamber and contained fluid-medium, diametrically movable 35 vanes or blades, an arching deflector-part movably positioned within the chamber and partially surrounding said vanes, whereby the action of the fluid-medium on the blades is controlled, and means for governing the 40 position of said deflector-part, substantially as set forth. —

2. In a variable-speed transmitting-appliance, the combination with a fluid-chamber associated with one of the members to be 45 operatively connected, of a plurality of rotatable blades or vanes disposed within said fluid chamber, and attached to the other member to be operatively connected, and a restricting controller-part movably positioned within said chamber, partially inclosing and adapted to govern the action of the 50 blades with respect to the fluid contained within said chamber, substantially as set forth.

55 3. In a variable-speed transmitting-appliance, the combination with a fluid-chamber associated with one of the members to be operatively connected, of a plurality of rotatable blades or vanes disposed within said 60 fluid-chamber, and attached to the other member to be operatively connected, and a deflector movably mounted within said chamber in position partially to inclose the rotatable blades, whereby the fluid within

the chamber may be placed under different 65 working pressures, and the transmitted speed of the motor altered, substantially as set forth.

4. In a variable-speed transmitting-mechanism, the combination with a casing forming 70 a fluid-chamber, and secured to one of the parts to be operatively connected, of a movable deflector within said chamber, and means for governing its position therein, and a plurality of blades or vanes rotatably positioned beneath the deflector and connected with the opposing part to be operatively connected; said blades or vanes being relatively movable under the control of the deflector, whereby the contained fluid may be placed 80 under varying working pressures, and the transmitted speed may be altered as required, substantially as set forth.

5. In a variable-speed transmitting-mechanism, the combination with a casing forming 85 a fluid-chamber, and secured to one of the parts to be operatively connected, of a movable deflector within said chamber, and means for governing its position therein, conical heads or disks positioned to engage 90 co-acting seats within the fluid chamber, and a plurality of blades or vanes rotatably positioned beneath the deflector and connected with the opposing part to be operatively connected; said blades or vanes being relatively 95 movable under the control of the deflector, whereby the contained fluid may be placed under varying working pressures, and the transmitted speed may be altered as required, substantially as set forth. 100

6. In a variable-speed transmitting-mechanism, the combination with a shaft to which power is applied, of a transmitting-member, comprising a core and a plurality of blades 105 diametrically movable therein, an arching movable deflector partially surrounding the blades, a sealed casing forming a fluid-chamber, wherein said parts are disposed and connected with the driven mechanism, a fluid-medium within said chamber, and external 110 means for governing the position of the deflector and rotatable blades, whereby the variation of speed is obtained, substantially as set forth.

7. In a variable-speed releasing-mechanism, the combination with an operating lever for apparatus of the class described, of a rack, a detent upon said lever for engaging the rack, an eccentric part normally permitting such engagement, and a releasing member associated with the eccentric for disengaging the rack from the detent, and thereby releasing the lever, substantially as set forth. 115

8. In a variable-speed transmitting-mechanism, the combination with a shaft to which power is applied, of a transmitting member, comprising a core mounting a plurality of blades diametrically movable with respect 125

thereto, conical heads disposed at either end of said core, valves positioned therein, a deflector surrounding the blades, a sealed casting forming a fluid-chamber, wherein said parts are disposed and connected with the driven mechanism, and a fluid-medium within said chamber controllable by the deflector and valves, substantially as set forth.

9. In a variable-speed transmitting-mechanism, the combination with a sealed fluid-chamber of an entering shaft; the said parts being respectively connected with the driving and driven members, rotatable blades or vanes secured to the shaft, conical heads engaging co-acting surfaces within the chamber, valves positioned within said heads, a deflector surrounding the rotatable blades and external means for controlling the position of said deflector, substantially as set forth.

10. In a variable-speed transmitting-mechanism, the combination with a sealed fluid-chamber of an entering shaft; the said parts being respectively connected with the driving and driven members, rotatable blades or vanes secured to the shaft, a deflector within the chamber partially surrounding the rotatable blades, and external means for control-

ning the position of said deflector, substantially as set forth.

11. In apparatus of the class described, two angularly positioned blades or vanes *h* *i*, the former being centrally cut away to permit the insertion of the latter; and said blades *i* being connected by a central web *t*, substantially as set forth.

12. In apparatus of the class described, the combination with a fluid-chamber and contained fluid-medium, a plurality of movable vanes or blades therein, a movable deflector-part within the chamber partially surrounding said vanes or blades, adapted to govern their position and resulting action upon the fluid-medium, an auxiliary chamber above the deflector, a valve controlling the same, and means for effecting the adjustment of the deflector-part, substantially as set forth.

Signed at Cleveland, this 19th day of January, 1907, in the presence of two subscribing witnesses.

AUGUST J. MEYER.
